(57) **CLAIM**

The ornamental design for a bottom shell for a handset, as shown and described.

DESCRIPTION

FIG. 1 is a left side view of a bottom shell for a handset showing my new design thereof;

FIG. 2 is a front view thereof;

FIG. 3 is a right side view thereof;

FIG. 4 is a bottom plan view thereof;

FIG. 5 is a perspective front view thereof;

FIG. 6 is a perspective rear view thereof; and,

FIG. 7 is a rear view thereof.

The broken line showing of the internal surface of the bottom shell in FIGS. 2 and 6 is for illustrative purposes only and forms no part of the claimed design. The broken line showing the indicia on the underside of the bottom shell in FIGS. 1, 4 and 5 forms no part of the claimed design.
